FLUID DISPENSER

Ozro N. Wiswell, Los Angeles, Calif., assignor to
Swingspout Measure Company, Los Angeles,
Calif., a corporation of California

Application January 9, 1934, Serial No. 705,896

14 Claims. (Cl. 221—23)

This invention relates to a fluid dispenser and relates more particularly to a fluid dispensing receptacle having means for opening cans or sealed containers. It is a general object of the present invention to provide a simple, practical fluid dispenser in the nature of a dispensing receptacle having novel and effective means for opening cans.

It is another object of the invention to provide a liquid dispensing receptacle having a cutter operable to open a can forced onto it, said cutter being disposed so that the force imparted to it during the opening of the can has no tendency to upset or overturn the receptacle. It is another object of the invention to provide a fluid dispenser in the nature of a receptacle having a means for opening a can to allow its contents to drain into the receptacle that is such that the exteriors of the receptacle and the opened can are not soiled or wet by the contents of the can.

It is another object of the invention to provide a dispensing receptacle having a cutter mounted within its upper portion that is positioned so that a can may be introduced into the upper end of the receptacle in an inclined position to be opened by the cutter and be thereafter supported in an inclined position to fully drain into the receptacle.

It is another object of the invention to provide a dispensing receptacle of the character mentioned having a cutter supported in its upper portion in an effective manner by a member which forms a guide for guiding cans onto the cutter.

It is another object of the invention to provide a dispensing receptacle having a cutter within its upper portion that is operable to cut a clean unobstructed opening in the lowermost part of an inclined can pushed into the upper end of the receptacle.

It is another object of the invention to provide a dispensing receptacle for handling lubricating oils, and the like, having an extension at the upper end for the reception of a can, and a cutter in the extension operable to open a can inserted in the extension, the said extension being operable to guide the can onto the cutter and to thereafter prevent the displacement of the can while the receptacle is being moved about.

It is a further object of the invention to provide a fluid dispensing device of the character mentioned that is simple and inexpensive of manufacture, and that is convenient to handle and use.

Other objects and features of the invention

will be best and fully understood from the following detailed description of typical forms and applications of the invention, throughout which description reference is had to the accompanying drawing, in which:

Fig. 1 is a longitudinal detailed sectional view of one form of the invention illustrating an opened can in position on the cutter. Fig. 2 is an enlarged fragmentary sectional view taken substantially as indicated by line 2—2 on Fig. 1 with the can removed. Fig. 3 is a fragmentary detailed sectional view taken as indicated by line 3—3 on Fig. 2. Fig. 4 is a side elevation of another form of the invention. Fig. 5 is a fragmentary side elevation of still another form of the invention with its upper portion broken away to appear in vertical cross section, and Fig. 6 is an enlarged fragmentary sectional view taken as indicated by line 6—6 on Fig. 5.

The form of the present invention illustrated in Figs. 1 to 3, inclusive, of the drawing, includes generally, a receptacle body 10, a shiftable valve controlled dispensing spout 11 on the body 10, and means 12 carried by the body 10 operable to open a sealed container or can C to cause its contents to drain into the receptacle.

The body 10 of the receptacle is provided to receive and hold fluid, for example, the fluid contents of a can or cans opened by the means 12, and in accordance with the invention, is provided with the swingable valve-controlled spout 11, and carries the can opening means 12. In the form of the invention being described, the body 10 includes a cylindrical shell or wall 13, and a bottom wall 14 extending across the lower end of the interior of the shell. The walls 13 and 14 provide a chamber 15 of round or cylindrical horizontal cross section having an open upper end for the reception of fluid and for the reception of a can. As will be subsequently described, the body 10 is proportioned so that its upper portion is sufficiently large to properly receive a can, of the size which the device is intended to handle, when the can is inclined in the manner illustrated in the drawing. The bottom wall 14 of the receptacle body 10 is preferably spaced above the lower end of the receptacle. Spaced discharge openings 16 are provided in the lower wall 14 of the body. A suitable handle 17 is provided on the shell or wall 13. In the particular instance illustrated, the upper end portion of the receptacle body 10 is plain or cylindrical and its upper edge is reinforced by a bead 18.

The spout 11 is provided to pour or discharge the fluid from the receptacle body 10, and in ac-

cordance with the invention, is operable or swingable between a substantially upright position and a down or discharge position. The movement of the discharge spout 11 governs or controls a valve that positively prevents the discharge of fluid from the receptacle chamber 15 into the spout prior to the operation of the spout to its discharging position. The particular spout 11 illustrated in the drawing is a rigid or unyielding tubular member including a comparatively long major or intermediate portion 20 that is adapted to be substantially vertically disposed adjacent the wall 13 of the body when the spout is in its up position. The outer end portion of the spout may be inclined or pitched relative to the portion 20.

The spout 11 has a bend or angle of substantially 90° adjacent its lower end so that its lower portion 21 projects inwardly under the bottom wall 14 of the body. A vertical opening or slot 20 is provided in the base portion of the receptacle to pass the lateral lower portion 21 of the spout. The lower end of the spout 11 is pivotally or swingably attached to the receptacle body 10 so that it may be freely swung between its up position and its down or discharging position. The mounting of the spout 11 includes a substantially transverse tubular member 22 arranged in the base portion of the body 10 below the bottom wall 14. The interior of the tubular member 20 is in communication with the discharge openings 16 of the receptacle. A transverse sleeve 23 is provided on the inner or lower end of the spout 11 and surrounds the member 22 in a manner to be turned or rotated thereon. The member 22 and the sleeve 23 may be longitudinally tapered and adjustable means 24 may be provided to urge the sleeve longitudinally of the member 22 in a direction to insure a leak-tight cooperation between the member and sleeve. As pointed out above, the flow of fluid from the receptacle chamber 15 to the spout is governed by a valve means controlled by movement of the spout.

The valve means includes or provides a port 25 in the lower wall portion of the tubular member 22 and a port 26 in the sleeve 23 communicating with the interior of the lower spout portion 21. The ports 25 and 26 are related so that they are out of communication or registration when the spout 11 is in its up or normal position and remain out of registration until the spout 11 has been swung downwardly a considerable distance to what I have termed its discharge position. It will be apparent how the flow of fluid from the receptacle chamber 15 to the spout 11 is positively prevented until the spout 11 is intentionally swung down to the required discharging position.

The means 12 is carried by the body 10 of the receptacle and is operable to cut an opening in a can pushed into the upper end portion of the body to allow the entire contents to freely drain from the can into the body. In the embodiment of the invention being described, the means 12 includes a cutter rigidly or fixedly mounted in the upper end portion of the body chamber 15 to open a can C pushed into the open upper end of the body. It is an important feature of the invention that the can opening means 12 is such that the can C is inclined downwardly and inwardly toward the center of the receptacle when pushed into the body to be opened so that the force employed to open the can has no tendency to overturn or upset the receptacle. The means 12 includes a support 27 for the cutter that acts as a guide to guide the can C onto the cutter.

In the particular form of the invention illustrated in Figs. 1 to 3 of the drawing, the support 27 is an elongate member extending downwardly and inwardly through the chamber 15 of the receptacle. The upper end of the support 27 is preferably connected with the shell or wall 13 of the body, while the lower end of the support is preferably attached to the bottom wall of the body. The upper end of the support 27 may be connected with the wall 13 in any suitable or practical manner, for example, it may have a hook part 28 engaging over the reinforcing bead 18 and welded to the outer side of the body as illustrated. A foot 29 is provided on the lower end of the support 27 and is connected with the bottom wall 14 in a suitable manner; for example, it may be welded to the wall 14.

The cutter of the means 12 is arranged on the support 27 in the upper portion of the receptacle chamber 15, and is substantially U-shaped in cross section, having two spaced parts 30 and a transversely curved outer part 31 connecting the parts 30. The cutter is disposed longitudinally of the support 27 and the inner edges 32 of the side parts 30 are inclined upwardly and outwardly to converge to a point 33 on the upper end of the part 31. The edges 32 are preferably flat and substantially normal to the side surfaces of the parts 30. In accordance with the invention, the cutter of the means 12 is mounted so that it is inclined downwardly and inwardly toward the center of the receptacle body 10. The outer part 31 of the cutter has its outer surface spaced from and substantially parallel with the opposing surface of the support 27 so that the cutter is inclined downwardly and inwardly with respect to the vertical center of the receptacle chamber 15. The lower end portion of the outer cutter part 31 is attached to a spacer or block 34 on the support 27 so that the outer surface of the part 31 is spaced from and parallel with the outermost face of the support 27. The block 34 forms a stop to limit inward movement of the can on the cutter. In practice the block 34 and the cutter are located so that they are above the level of the liquid drained from the can into the body 10, so that the exterior of the can is not wet or soiled by the liquid. Spaced openings 35 are provided in the walls of the cutter to permit the contents of the can C to freely drain out through the cutter when the cutter has reached its final opened position illustrated in Fig. 1.

It is believed that the operation of the form of the invention illustrated in Figs. 1, 2 and 3 of the drawing will be readily understood from the foregoing detailed description. The can opening cutter and its support 27 are comparatively small and do not obstruct the open upper end of the body 10 so that the receptacle may be employed in the usual manner for the handling of fluids such as bulk oil. When it is desired to open a sealed container or can C of fluid to dispense its contents from the receptacle, the can is held in an inclined position where its exterior or lower bead engages the upper exposed end part of the support 37. The can is then thrust or pushed downwardly and inwardly toward the center of the receptacle chamber so that the point 33 pierces its lower wall or end at a point immediately adjacent the periphery of the can. Downward movement of the can on the cutter causes the flaring or diverging upper portions of the edges 32 to widen or enlarge the cut made by the point 33, while continued downward movement of the can results in the outer longitudinal corners of the

edges 32 cutting or shearing the end wall of the can. The flat edges 32 operate to cause the flap F outlined by the cut to be rolled upwardly and inwardly somewhat in the manner illustrated in Fig. 1 of the drawing. The cut thus formed by the cutter is comparatively large and is entirely unobstructed to allow the free draining of the contents from the can C into the receptacle chamber 15. The support 27 operates to guide and stabilize the can C when it is forced downwardly on the cutter and aids in holding the can C in the tilted position after being opened by the cutter. The opening formed by the cutter is in the extreme lower corner or part of the can so that the entire contents of the can may quickly drain into the receptacle. The openings 35 in the cutter permit the fluid in the can to drain out from around the cutter. To pour or drain the fluid from the receptacle, the spout 11 is swung downwardly to a position where its lower end discharges into the receiver or receiving container. This brings the port 26 into register with the port 25, allowing the fluid to freely drain out through the spout. In actual practice, the opened can may remain on the cutter in its tilted position as the fluid is drained from the receptacle 16, thus allowing the entire contents to drain from the can C without loss of time. When the can C is emptied, it may be quickly and easily disengaged from the cutter and removed from the device. It is to be noted that the contents of the can C cannot be spilled or lost from the receptacle and do not wet or soil the exterior of the can or receptacle body. The device is particularly simple and convenient to use, and is sturdy and inexpensive of manufacture.

The form of the invention illustrated in Fig. 4 of the drawing includes a receptacle body 10 having a swingable spout 11^a and a can opening means 12^a which elements are identical with the corresponding elements of the form of the invention described above. It is to be understood that the spout 11^a controls or is operatively related to a valve in the same manner as the spout 11 and is swingable from the upright position illustrated to the down or discharging position. The means 12^a includes a cutter 38 mounted in an inclined position on an inclined support 27^a in the upper portion of the receptacle to cut an opening in a can pushed downwardly onto it.

The form of the invention illustrated in Fig. 4 is characterized by an extension 39 on the receptacle body 10^a for receiving and guiding a can when it is pushed onto the cutter 38, and a closure or cover 40 for closing the upper end of the receptacle. The upper end of the body 10^a proper is provided with an arched or convexed inwardly extending rim 41. The can-receiving extension 39 projects upwardly from the rim 41. In accordance with the invention, the extension 39 is shaped and proportioned to slidably or freely receive the cans for which the device is intended. It will be obvious that the extension 39 may be proportioned and shaped to receive typical cans of various capacities and configurations, for example, cylindrical cans of one quart capacity, or two quart capacity, etc. In the case illustrated, the extension 39 is cylindrical in transverse cross section to receive the usual cylindrical type of can. In accordance with the invention, the longitudinal axis of the extension 39 is parallel to the guide 27^a and cutter 38, that is, it is inclined downwardly and inwardly with respect to the receptacle body 10^a. The upper end or edge 42 of the extension 39 may be beaded or rolled. The lowermost part of the end or bead 42 may join or be

immediately adjacent the rim 41 at a point in longitudinal alignment with the cutter 38, and support 27^a. It will be apparent how the extension 39 on the receptacle body 10^a is operable to receive and guide a can when it is forced downwardly onto the cutter 38, and how it aids in retaining the can in the desired inclined position to drain into the receptacle when the receptacle is moved about or tipped.

The cover 40 is provided to close the upper end 10 of the receptacle body 10^a against the entrance of dust, etc. The cover 40 is connected with the bead 42 or upper end portion of the extension 39 by a pivct or hinge connection 43. In the preferred construction, the closure or cover is pivoted to the extension 39 at a point in longitudinal alignment with the cutter 38 and support 27^a, and is adapted to be opened to an inclined position where it is parallel with the guide and support 27^a. A stop lug 44 may be provided at the hinged connection of the cover 40 to limit or stop the outward movement of the cover at the position just described. It will be apparent how the cover 40 may be operated from its closed position, where it cooperates with the bead 42 to close the upper end of the receptacle, to the open position illustrated where it leaves the upper end of the extension unobstructed for the reception of the can.

The form of the invention illustrated in Figs. 5 and 6 of the drawing includes, generally, a receptacle body 10^b, a shiftable or swingable spout 11^b on the body, an upwardly projecting can-receiving extension 45 on the upper end of the body 10^b, and can opening means 46 in the extension.

The body 10^b and the spout 11^b may be identical with the body 10 and spout 11 previously described. In the particular construction illustrated in Fig. 5 of the drawing, an arched or convexed rim 47 is provided in the upper end of the body 10^b. It is to be noted that the body 10^b may be employed as a measure, as the can opening means 46 is entirely external of the fluid-containing interior of the body.

The extension 45 carries the can opening means 46 and is adapted to receive the lower end portion of a can pushed or moved downwardly into it to be opened by the means 46. The extension 45 projects upwardly from the inner edge of the rim 47 and is preferably axial relative to the vertical axis of the body 10^b. In accordance with the broader principles of the invention, the extension 45 may be shaped and proportioned to receive any particular character of sealed container. In the simple form of the invention being described, the extension 45 of the receptacle body is cylindrical to receive the typical or usual cylindrical can. If desired or found practical, the extension 45 may be formed of a separate part attached to the body 10^b; however, it may be preferred to form the extension 45 integral with the rim 47 of the body as illustrated in the drawing.

The means 46 is provided within the extension 45 to open a can pushed or forced downwardly into the extension. The means 46 may include two or more cutters 48. In the case illustrated in the drawing, there are two cutters 48 at diametrically opposite points on the inner wall of the extension 45. The cutters 48 are longitudinally or vertically disposed in the extension 45 and are substantially U-shaped in horizontal cross section, each having spaced side parts 49 and a transversely curved outer part 50 connecting the parts 48. The inner edges 51 of the parts 49

are inclined upwardly and outwardly to converge at a point 52 on the upper end of the part 50. The edges 51 of the cutters are preferably flat and substantially normal to the surfaces of the side parts 49 so that their outer corners operate to shear or cut the end wall of the can as it is moved downwardly through the extension 45. The cutters 48 have their lower end portions attached to or supported on blocks 53 which space the outer parts 50 of the cutters from the inner wall of the extension 45. This mounting of the cutters positions the cutters so that their points 52 are adapted to pierce the end wall of a can immediately adjacent its periphery whereby the cutters form openings which extend inwardly from the periphery of the can to allow the entire contents to drain directly into the receptacle body 10b. Openings 54 are provided in the walls of the cutters 48 to permit the contents of the can to drain out from around the cutters.

It is believed that the operation of the form of the invention illustrated in Figs. 5 and 6 of the drawing will be readily understood from the foregoing detailed description. When a can is pushed downwardly into the extension 45 of the receptacle body, the pointed upper ends 52 of the cutters pierce the end wall of the can immediately adjacent its periphery so that the cutters form openings which extend inwardly from the periphery of the can. The flat edges 51 of the cutters cause the flaps outlined by the cuts to be rolled inwardly, leaving the openings entirely unobstructed. The extension 45 forms an effective guide for guiding the can onto the cutters, and aids in supporting the can on the cutters when its contents are being drained into the receptacle.

Having described only typical forms and applications of my invention, I do not wish to be limited or restricted to the specific forms or applications herein set forth, but wish to reserve to myself any modifications or variations that may appear to those skilled in the art or fall within the scope of the following claims:

Having described my invention, I claim:

1. A fluid handling device including, a body having an open topped fluid chamber, there being an outlet at the lower end of the chamber, a shiftable discharge spout, valve means controlling communication between the outlet and spout, an inclined member in the chamber attached to the bottom wall of the chamber and the upper wall portion of the body, and a cutter carried by the member for opening a container to have the contents thereof drain into the chamber.

2. A fluid handling device including, a body having an open topped fluid chamber, there being an outlet at the lower end of the chamber, a shiftable discharge spout, valve means controlling communication between the outlet and spout, and means carried by the body for opening a container to have the contents thereof drain into the chamber, the last mentioned means including a cutter, and an inclined member rigidly supporting the cutter in the body where it is inclined downwardly toward the center of the chamber to cut an opening in a container forced onto it.

3. A fluid handling device including, a body having an open topped fluid chamber, there being an outlet at the lower end of the chamber, a shiftable discharge spout on the body operable to a position where it may be inserted in a fluid receiving tube to support the body thereon,

valve means controlling communication between the outlet and spout, a cutter, and an inclined member rigidly mounting the cutter in the body to cut an opening in a container and support the container in an inclined position with said opening in its lowermost part to drain the contents of the container into the chamber.

4. A device of the character described including, an open topped receptacle body, there being an outlet at the lower end of the body, a shiftable spout on the body for carrying fluid from the outlet, a cutter, and an inclined support operable to guide an inclined can introduced into the body and rigidly supporting the cutter in the body in the inclined position to open an inclined can whereby its contents may drain into the body.

5. A device of the character described including, an open topped receptacle body, there being an outlet at the lower end of the body, a shiftable spout on the body for carrying fluid from the outlet, valve means governing the communication between the spout and outlet controlled by movement of the spout, an inclined cutter in the upper portion of the body, and a support carrying the cutter and having an inclined surface for guiding an inclined can against the cutter.

6. A device of the character described including, an open topped receptacle body, there being an outlet at the lower end of the body, a swingable spout on the body for carrying fluid from the outlet, valve means governing the communication between the spout and outlet controlled by movement of the spout, a cutter in the upper portion of the body, and means supporting the cutter and having a surface for guiding a tilted can downwardly and inwardly onto the cutter to be opened thereby.

7. A device of the character described including, a body having an open topped fluid chamber, there being an outlet at the lower end of the chamber, a shiftable discharge spout, valve means controlling communication between the outlet and spout, a cutter in the upper end of the body, and a guide for guiding a can onto the cutter in an inclined position to be opened thereby.

8. A device of the character described including, an open topped receptacle body, there being an outlet at the lower end of the body, a cutter, and means supporting the cutter in the upper portion of the body where it faces upwardly and is inclined downwardly and inwardly relative to the center of the body, said means having a surface to guide a can downwardly and inwardly onto the cutter.

9. A device of the character described including, an open topped receptacle body, there being an outlet at the lower end of the body, an upwardly facing cutter rigidly supported in the upper portion of the body inclined downwardly and inwardly relative to the vertical axis of the body, and an inclined tubular extension on the upper end of the body operable to guide an inclined can downwardly and inwardly onto the cutter.

10. A device of the character described including, an open topped receptacle body, there being an outlet at the lower end of the body, an upwardly facing elongate cutter of substantially U-shaped transverse cross section rigidly supported in the upper portion of the body and inclined downwardly and inwardly relative to the vertical axis of the body, there being a point on

the upper end of the cutter and the longitudinal edges of the side parts of the cutter being convergent toward the point, and means for guiding a can onto the cutter.

5 11. A device of the character described including, an open topped receptacle body, there being an outlet at the lower end of the body, an elongate cutter of substantially U-shaped transverse cross section in the upper portion of the 10 body and inclined downwardly and inwardly relative to the vertical center of the body, there being a point on the upper end of the cutter and the longitudinal edges of the side parts of the cutter being convergent toward the point, and 15 means supporting the cutter and having an inclined face for guiding a can onto the cutter.

12. A device of the character described including, a receptacle body having cylindrical side walls and a bottom wall, an upwardly facing cutter, and inclined supporting and guiding means 20 mounting the cutter within the body a substan-

tial distance above the bottom wall to open an inclined can introduced into the upper end of the body.

13. A device of the character described including, a receptacle body having cylindrical side walls and a bottom wall, a member extending downwardly from the upper end of the side walls and inclined downwardly and inwardly toward the center of the bottom wall, and a cutter on said member operable to open a can moved 10 downwardly on said member in an inclined position.

14. A device of the character described including a receptacle body having cylindrical side walls and a bottom wall, there being a controlled outlet in the bottom wall, a cylindrical axial extension on the upper end of the body adapted to receive a can, and spaced cutters rigidly supported in the extension operable to open the can. 15
